(57) **CLAIM**

The ornamental design for a vehicle rim with dollar signs, crescents, and disc, as shown and described.

DESCRIPTION

FIG. 1 is a front perspective view of a vehicle rim with dollar signs, crescents, and disc showing our new design; FIG. 2 is a front elevation view thereof; FIG. 3 is a left elevation view thereof; and, FIG. 4 is a right elevation view thereof.

The broken lines of environmental structure in FIG. 1, FIG. 3, and FIG. 4 of the drawings are for illustrative purposes only and form no part of the claimed design.

A rear elevation view of the vehicle rim has been omitted because this view is plain and unornamented.
